UNITED STATES PATENT OFFICE.

WILLIAM W. GRISCOM, OF HAVERFORD COLLEGE, PENNSYLVANIA, ASSIGNOR
TO THE ELECTRO DYNAMIC COMPANY OF PHILADELPHIA.

DYNAMO-ELECTRIC MACHINE.

SPECIFICATION forming part of Letters Patent No. 393,469, dated November 27, 1889.

Application filed June 30, 1888. Serial No. 278,634. (No model.)

To all whom it may concern:

Be it known that I, WILLIAM W. GRISCOM, a citizen of the United States, and a resident of Haverford College, in the county of Montgomery and State of Pennsylvania, have invented certain new and useful Improvements in Dynamo-Electric Machines, of which the following is a specification.

My invention is an improvement in details of construction of dynamo-electric machines or motors.

The improvements specially concern the construction of the armature.

I form my armature-core from a series of convolutions of soft-iron wire wound upon a frame-work. This frame-work itself I also construct of soft iron. The use of such wire avoids the circulation of magnetic variations or magnetic eddies. By using a frame-work of magnetic material—as iron—I add to the magnetic volume and provide a frame-work of considerable strength without the addition of much weight. If clean iron strips were used, these several successive convolutions of the wire would be magnetically united—that is, the benefits due to the use of the wire would be neutralized by connecting one convolution with another in such a manner that magnetic currents, eddies, or variations could circulate in the entire mass of iron as a whole; but by covering the surface of this frame-work with a non-magnetic metal such connection is avoided and each convolution, as well as the frame-work, is magnetically independent. I have found tinned iron to answer this purpose exceedingly well, and I therefore construct the frame-work of my armature of tinned iron. By placing in position a frame-work of tinned iron and winding one or more layers of the iron wire thereon, then placing in position a second series of tinned-iron strips and winding more iron wire thereon, I am enabled to produce a firmer and a more mechanically perfect armature-core.

The accompanying drawings illustrate my invention.

Figure 1 is an end view. Fig. 2 is a longitudinal section. Fig. 3 is a detail.

R indicates a ring of cast-iron, having a cross-section, as shown in Fig. 2.

S is a spider, preferably of brass, having four or more arms or projections entering

notches f in the iron rings R, and serving to support the rings, and to thus equalize and distribute the points of support of the weight of the armature. These spiders are keyed to 55 a shaft, s, in the usual manner. At intervals I fix a series of strips of tinned iron, n, to corresponding peripheral points of the two rings, each and every strip of this series being at the same radial distance from the center, and I 60 rivet these strips n to the shoulder of the ring R, as at r. Each strip of this series is separated from the one next succeeding by an equal circumferential distance. A second series of tinned-iron strips, m, are placed at equal circumferential distances, each and every strip 65 being located at an equal radial distance at points between the first-named series of strips and the center, but in every case in the same radial line. On both sides of both series of 70 strips, and also between these tinned-iron strips, I place soft-iron wire of comparatively large gage, which I prefer to wind on in the direction of rotation. By this means magnetic eddy-currents are almost entirely avoided. 75 The armature is aired and retained at a low temperature under the effects of continued use, and the weight of the structure is equally distributed, while for its generative power the armature is extremely light. 80

The copper conducting-wire is wound and connected to commutator-segments after what is generally called the "Gramme" plan, and the field-magnets are of any well-known construction.

What I claim, and desire to secure by Letters Patent, is—

1. The combination, in a dynamo-electric machine, of an armature composed of two parallel cast-iron rings, strips of tinned iron uniting said rings at equidistant circumferential points, and one or more layers of soft-iron wire enveloping said strips in non-magnetic contact therewith. 90

2. The combination, in a dynamo-electric machine, of an armature composed of two parallel cast-iron rings, two concentric series of tinned-iron strips, having their opposite ends connected to said rings, respectively, and one or more layers of soft-iron wire enveloping 95 said strips in non-magnetic contact therewith. 100

3. In a dynamo-armature, the combination

of two parallel cast-iron rings respectively connected to a rotating shaft by spiders of non-magnetic material, a series of tinned-iron strips connecting the two rings, and one or 5 more layers of soft-iron wire uniformly disposed upon or around the said strips, substantially as described.

Signed at New York, in the county of New York and State of New York, this 28th day of June, A. D. 1888.

W. W. GRISCOM.
